UNITED STATES PATENT OFFICE.

HERBERT A. BOLDT, OF BUFFALO, NEW YORK.

STREET-CLEANING APPARATUS.

1,427,188.

Specification of Letters Patent. Patented Aug. 29, 1922.

Application filed July 10, 1920. Serial No. 395,188.

To all whom it may concern:

Be it known that I, HERBERT A. BOLDT, a citizen of the United States, residing at Buffalo, in the county of Erie and State of 5 New York, have invented new and useful Improvements in Street-Cleaning Apparatus, of which the following is a specification.

This invention relates to a self-propelled apparatus which is adapted to remove ob- 10 jectionable material, such as snow, from the street or highway.

One of the objects of the invention is to break up and forcibly push the objectionable material back into the shovel of the apparatus even when said material is firmly compacted together and banked high up in the path of the machine.

A further object of the invention is to provide for the folding up of the conveyor 20 when not in use so as to reduce the size of the apparatus when the same is idly trav- 25elling along the street to or from its work.

A still further object of the invention is to permit of the conveyor being so secured 30 relatively to the frame of the apparatus, that the same may be extended to either one side or the other of the machine as may be desired with suitable provision made for the reversal in direction of movement of the conveyor belt which is thereby required.

A still further object of the invention is the provision of yieldable connections be- 35 tween the principal working parts of the apparatus so that danger of fracturing the same is avoided when the apparatus at- tempts to break up and remove impene- trable or heavy matter.

In the accompanying drawings:

Figure 1 is a side elevation of the com- 40 plete street cleaning apparatus which is the subject of the present invention. Figure 2 is a vertical longitudinal section through the apparatus taken on line 2—2, Fig. 4. Figure 3 is a fragmentary horizontal section 45 taken on line 3—3, Fig. 2, and showing the means of reversing the movement of the conveyor belt. Figure 4 is a rear elevation of the street cleaning apparatus. Figure 5 is a fragmentary rear elevation of the ap- 50 paratus and similar to Fig. 4, but with the

conveyor extending out from the opposite side of the apparatus. Figure 6 is an enlarged fragmentary side elevation of the yieldable joint of the oscillating lever and co-operating parts. 55

Similar characters of reference indicate corresponding parts throughout the several views.

10 represents the main horizontal plat- form or frame plate of the street cleaning 60 apparatus, the same being adapted to be moved along the street or roadway which is to be cleaned. For this purpose of port- ability, the platform 10 is preferably pro- 65 vided at its front and rear ends with trans- versely disposed front and rear axles whose outer ends carry the large tread-wheels 11 and 12 respectively, which receive the front and rear turns of the endless horizontal belt treads 13. Intermediately of the main tread 70 wheels, these belt treads are suitably sup- ported by intermediate smaller tread wheels 14. Extending upwardly from the four corners of the main platform 10 are the front and rear supporting bars 16 and 17 75 which diverge longitudinally and outwardly away from each other, and are connected longitudinally together by means of a pair of longitudinally disposed but inclined ele- 80 vator plates 18 which are arranged with their flat faces vertical and parallel to each other. The foregoing elements constitute the principal parts of the main frame of the apparatus, the same being propelled along the ground by a suitable hydrocarbon or 85 other prime mover 20 which drives the back axle of the apparatus through the medium of a chain belt 21 and suitable sprocket wheels mounted respectively on said back axle and the crank shaft of the prime mover. 90

Transversely pivoted at 22 to the frame of the apparatus and received between the elevator plates 18, is a normally inclined sheet metal scoop 23 whose lower or front end is adapted to sweep forwardly on top 95 of or near the surface of the street which is being cleaned. When the whole apparatus is traveling idly along the street to or from the place where it is operating, it is desirable to hold this scoop 23 in an ele- 100

vated or inoperative position, as indicated by the dotted lines of Fig. 2. This is accomplished by means of a small winch 25, which is transversely journaled in the frame of the machine and has wrapped around its middle part a flexible hoisting cable 26, the rotation of the winch being accomplished manually by a suitable crank arm 27 and suitably held in position by the usual dog and ratchet mechanism (not shown). The cable 26 passes up through a vertical guide hole which is formed centrally in a transverse frame or stiffening bar 30 and is made fast to a suitable gripping hook 31 which is adapted to be secured to the front edge of the scoop 23 for the purpose of elevating the same by means of said winch.

Transversely journaled at opposite ends of the elevator plates 18 are the front and rear elevator shafts 32 and 33, respectively, to which are secured the sprockets 34. Arranged with its opposite turns about said sprockets is an endless elevator chain belt 35 which is driven from the prime mover 20 in a manner hereinafter to be described. Secured at suitable intervals to said endless chain belt 35 are a plurality of elevator blades or buckets 36 each of which is arranged to project outwardly from said chain belt at substantially a right angle thereto. The lower stretch of said chain belt 35 together with its elevator blades moves upwardly and rearwardly of the machine, thereby elevating the material which it is desired to have removed from the street, said material flowing from the upper face of the aforesaid scoop 23 backwardly and upwardly on the upper surface of an inclined transverse platform or runway 38, which extends across between the inner faces of the inclined elevator plates 18 adjacent to the lower edges of the blades 36.

Secured to the opposite ends of the front transverse elevator shaft 32 and outwardly of the frame of the apparatus, is a pair of crank arms 40, whose eccentric crank pins 41 are pivotal to the central parts of a pair of longitudinally-disposed oscillating levers 42. Pivoted to the upper central part of the main frame of the apparatus on each side thereof at 39 is a link 43 whose lower end is yieldably pivoted at 44, as shown in Figs. 1 and 6, to the extreme rear end of its companion oscillated lever 42. This yieldable connection consists of a helical compression spring 45 which is let into a suitable slot 46 in the lower end of each link 43 and bears with its lower end against the end face of said slot 46 while its upper end bears against the lower face of the pivot pin 44, which latter is free to move vertically within said slot. Thus when an unduly great upward force is exerted on the front end of the oscillating lever 42, the pivot pin 44 thereof instead of acting directly on the link 43,

presses resiliently downwardly against the said compression spring 45.

The two oscillating levers 42 are joined at their extreme front ends by a transverse tie bar 47, to which is secured a rearwardly and longitudinally-extending arm 48. To the front downward portion of said arm 48 are secured one or more picks or digger fingers 50 which project downwardly at a right angle thereto and are adapted to dig into and break up any large, heavy or compacted masses of material which may lie in the path of the machine in the manner shown by dotted lines in Fig. 1. When any one or more of these picks become broken or unduly worn down, the same may be removed by cutting off the rivets 51 and replacing the said picks. Centrally of the arm 48 is secured a downwardly-projecting vibrating bracket 52 to whose lower end is suitably secured a transversely disposed vibrating finger 53. The mechanical or structural connection between this vibrating finger and the oscillating levers 42 is very indirect and hence is of a resilient nature, as is apparent from the construction, so that, as the said oscillating levers are driven in a curved path by means of the cranks 40 and as the whole machine moves along the street, this vibrating finger is caused to whip back and forth by reason of the combined vibration of the machine and the irregularity of the piles of material. Such a resilient or a whipping, vibrating action facilitates the entrance into and the removal of the material by said vibrating finger. At the extreme rear end of the arm 48 is secured a depending inclined, transversely disposed shovel plate 55 which is narrow enough to be easily received between the vertical side walls of the scoop 23, the movement of said shovel plate at the lower part of its stroke being substantially parallel to the lower floor plate of said scoop. Thus any material which may lie at or near the mouth of said scoop is pushed rearwardly up into said scoop by said shovel plate, and thereby into the path of action of the blades 36 of the endless elevator chain belts 35.

The elevator at its upper end discharges or drops the material onto the upper stretch of a transversely disposed conveyor belt 56 whose opposite turns pass around belt pulleys 57 and which is centrally supported by a supporting pulley 58 and is guided downwardly upon the upper face of its lower stretch by means of a pair of guide pulleys 59, all of said pulleys being preferably dished, as shown in the drawings. This conveyor belt is driven by a suitable chain 60 which passes with its opposite turns around suitable sprocket wheels 61 which are secured to the rear ends of the shafts upon which said end belt pulleys 57 are mounted and to which they are secured. The lower stretch

of the conveyor chain belt preferably passes around a pair of suitable guide wheels 610 that are preferably not provided with sprocket teeth but are merely dished. The 5 said chain 60 is driven by and meshes with a driving sprocket 62, the chain being held thereagainst so as to remain positively in engagement therewith by reason of an idler or jack sprocket wheel 63 which is mounted 10 on a suitable short stud shaft 64. The said driving sprocket 62 is secured to the rear end of a longitudinal, horizontal drive shaft 65 which is suitably journaled in the main frame of the machine and carries at its extreme front end, a crown gear 66. The latter, as best shown in Fig. 3, is adapted to mesh on either the one or the other of its sides with a spur gear 67 which is adapted to be secured in either of said positions upon the 15 spline 68 of a transverse shaft 69 by means of a set screw 70, said transverse shaft being suitably journaled at 71, 71 in the frame of the machine. Pinned or otherwise permanently secured to said transverse shaft is an 20 intermediate sprocket wheel 73 which is driven by a chain belt 74 whose lower turn engages with a rear axle sprocket wheel 75 which is secured to the rear axle of the apparatus. This rear axle is power connected to 25 the engine or prime mover 20 by means of the chain belt 21, as heretofore described, suitable friction clutches being interposed in this or any other of the power lines, if desired. The one outer end of said transverse 30 shaft 69 is provided with a small elevator driving sprocket wheel 76 which engages the lower turn of an elevator belt chain 77 which latter in turn drives the rear transverse elevator shaft 33 heretofore described. The 35 power transmission to the conveyor belt may be completely disconnected by shifting the spur gear 67 to any position intermediate of the positions thereof shown in Fig. 3, in which case the teeth of the same will not 40 mesh with the teeth of the crown gear 66.

Referring to Fig. 4, it will be seen that the conveyor belt 56 is mounted on a conveyor frame having a knuckle or hinge joint 78 in the middle thereof, so that the 45 projecting part of the conveyor may be folded up vertically, so as to make the apparatus more compact when the same is traveling idly along the street. This folding action, it will be noticed, does not interfere 50 with the conveyor chain belt 60, inasmuch as the hinge joint 78 of the conveyor frame is positioned outwardly of the jack or idler sprocket wheel 63, so that, as a result, said conveyor chain belt 60 merely becomes less 55 taut when the outer end of the conveyor is folded up, which feature of construction is a distinct advantage when said chain belt is to be replaced or repaired.

The conveyor frame comprises two pairs 60 of transversely disposed, parallel conveyor

beams 80 and 81. In the arrangement there- 65 of shown in Fig. 4, each of the beams 81 is secured to the main frame of the apparatus by removable bolts 82, and rests upon a pair of horizontal, longitudinal stringers 83 70 so as to relieve the stress which would otherwise be imposed on the said removable bolts 82. When operating conditions make the same desirable, the conveyor beams 80 may be directly secured to the machine, as shown 75 in Fig. 5, instead of the beams 81. In such case the hinge or knuckle joint 78 operates precisely as before, allowing the outer part of the conveyor frame to be folded up vertically. Such a rearrangement of the conveyor 80 requires of course that the conveyor belt be driven in the opposite direction. This is accomplished by shifting the spur gear 67 to the opposite side of the crown gear 66 as heretofore described. 85

I claim as my invention:

1. A street cleaning apparatus comprising a frame, an endless belt elevator, a scoop pivoted to said frame in front of said elevator, a crank journaled on said frame, a vertically oscillating lever pivoted centrally to said crank, a link pivoted at opposite ends to the rear end of said oscillating lever and to the said frame, and a shovel plate connected to the front end of said oscillating 90 lever and positioned at all times in substantially the same angular position.

2. A street cleaning apparatus comprising a frame, an endless belt elevator, a scoop pivoted to said frame in front of said ele- 100 vator, a crank journaled on said frame, a vertically oscillating lever pivoted centrally to said crank, a link pivoted at opposite ends to the rear end of said oscillating lever and to the said frame, and a shovel plate connected to the front end of said oscillating lever and arranged to move substantially 105 parallel to the upper surface of the scoop at the lower portion of its stroke.

3. A street cleaning apparatus comprising a frame, an elevator, a conveyor projecting out from the apparatus proper and provided with a knuckle joint whereby the two halves of the conveyor may be folded relatively to each other, and means arranged 110 to permit of either half of said conveyor being rigidly secured to the apparatus proper so as to permit of the companion half of said conveyor being folded vertically.

4. A street cleaning apparatus comprising a frame, an elevator, a conveyor provided centrally with a knuckle joint and so arranged that either desired half of said conveyor may be secured rigidly to the said frame of said apparatus and the other half 115 folded vertically relatively thereto, conveyor belt pulleys journaled at opposite ends of said conveyor and provided with sprockets, a driving sprocket journaled centrally of the frame of the apparatus, and a chain 120

belt passing around said driving sprocket and said belt sprockets.

5. A street cleaning apparatus comprising a frame, an elevator, a transversely disposed conveyor projecting out from the apparatus proper and power driven from a driving sprocket shaft, a crown gear mount-

ed on said shaft, a driving spur gear mounted on a transverse power shaft and capable of being shifted along said shaft so as to mesh with either desired side of said crown gear, and means for driving said transverse shaft. ¹⁰

HERBERT A. BOLDT.
